UNITED STATES PATENT OFFICE.

JACOB R. DEILY, OF PHILADELPHIA, PENNSYLVANIA.

TROLLEY.

No. 820,481.

Specification of Letters Patent.

Patented May 15, 1906.

Application filed September 5, 1905. Serial No. 276,953.

To all whom it may concern:

Be it known that I, JACOB R. DEILY, a citizen of the United States, residing at Philadelphia, county of Philadelphia, and State of Pennsylvania, have invented a new and useful Improvement in Trolleys, of which the following is a full, clear, and exact description, reference being had to the accompanying drawings, which form a part of this specification.

My invention relates to trolleys of the two-wheel type, and has for its object to so construct the trolley as to avoid serious results in case the trolley jumps off the conducting-wire and strikes a cross-wire or other obstruction.

The invention consists of a pole to which is pivoted a reversible wheel-frame adapted to revolve three hundred and sixty degrees on its pivot, the construction being such that the wheel-frame is pivoted substantially at its center of gravity and carries at its opposite free ends the two trolley-wheels, whose axes are normally in horizontal alinement with the pivot of the wheel-frame.

A two-wheeled trolley possesses certain advantages, chief among which is the greater certainty with which it maintains contact with the conducting-wire. If, however, for any reason it slips off the wire and contacts with an obstruction, such as a cross-wire, it catches or hooks in the cross-wire, and if the car is going at any speed is liable to tear the cross-wire from its fastenings, causing the conducting-wire to drop and damage the car and imperil the safety of the passengers. Moreover, the trolley itself is likely to sustain serious injury. If, however, a trolley constructed in accordance with my invention slips off the conducting-wire and contacts with a cross-wire or any other obstruction the latter as it is engaged by the wheel-frame causes the wheel-frame to revolve on its pivot and at the same time permits the wheel-frame to pass freely under the cross-wire.

My invention will be more readily understood by reference to the accompanying drawings, in which—

Figure 1 is a plan view of the wheel-frame and the upper end of the pole. Fig. 2 is a side elevation of the same. Figs. 3, 4, and 5 are diagrammatic views showing the successive positions assumed by the wheel-frame when disengaged from the conducting-wire and while passing a cross-wire.

a is the trolley-pole provided at its upper

end with arms *b b*, forming a fork to receive the wheel-frame *e*. The outer ends of the arms *b b* are provided with the inwardly-extending bearings *c c*, between which is secured a pin *d*, on which the trolley-wheel frame *e* freely turns. The wheel-frame is thus pivotally secured to the trolley-pole and is free to revolve completely about its axis. The outer ends of the wheel-frame are provided with the arms *f f* and *g g*, forming forks to receive the wheels *h* and *i*, respectively.

j and *k* are pins secured between the arms of the forks *f f* and *g g*, respectively, and on which the wheels *h* and *i*, respectively, freely revolve.

The trolley-wheel frame is pivotally secured at substantially its center of gravity, and the pivotal connections are so arranged that a straight line connecting the axes of the trolley-wheels intersects the pivot of the wheel-frame.

l is the usual rope by which the trolley-pole is operated by the conductor. The rope is secured to the pole itself at *m* and not to the wheel-frame.

I will now describe the operation of the trolley in case it jumps from the conductor-wire and strikes a cross-wire. Fig. 3 illustrates such a disengaged trolley just before contacting with a cross-wire *w*. Fig. 4 illustrates the trolley just after it has struck the cross-wire. It will be observed that the action of the cross-wire upon the trolley is to turn the wheel-frame on its pivot. Fig. 5 illustrates the trolley while it is still engaged with the cross-wire and just before it has freed itself therefrom. It will be observed that the wheel-frame still continues to turn on its pivot, and it will be understood that after it has turned approximately one hundred and eighty degrees it will free itself entirely from the cross-wire. The operation described imposes no strain on the cross-wire that it is not easily able to withstand. The force with which the wheel-frame contacts with the cross-wire is sufficient ordinarily to cause the wheel-frame to spin a number of times about its axis; but it will speedily come to rest.

It is easy to reset the trolley. It is only necessary for the conductor to manipulate the pole so as to bring one of the wheels in contact with the conducting-wire, and the upward tension of the pole will cause the other wheel to set itself. The arrangement of the pivotal connections being as before de-

scribed, it will be understood that the trolley will work equally well whether the wheel-frame is in the position shown in Figs. 1 and 2, in which the wheel *h* is in advance of the wheel *i*, or whether the wheel-frame is reversed, so that the wheel *i* is in advance of the wheel *h*.

Having now fully described my invention, what I claim, and desire to protect by Letters Patent, is—

1. In a trolley, the combination with a pole, of a wheel-frame pivoted thereto at about its center of gravity and freely revolvable completely around the same, and grooved trolley-wheels pivoted at opposite ends of the wheel-frame and adapted to normally simultaneously engage the conducting-wire, the pivotal connections being so arranged that a straight line connecting the axes of the trolley-wheels intersects the pivot of the wheel-frame.
2. In a trolley, the combination with a pole having a forked outer end, a wheel-frame within the fork of the pole reversible and freely revolvable in bearings on the outer ends of the pole-fork, and grooved trolley-wheels

pivoted at the opposite ends of the wheel-frame, the pivotal connections being so arranged that a straight line connecting the axes of the trolley-wheels intersects the pivot of the wheel-frame.

3. In a trolley, the combination with a pole having a forked outer end, a wheel-frame within the fork of the pole and reversible and freely revolvable in bearings on the outer end of the pole-fork, grooved trolley-wheels pivoted at opposite ends of the wheel-frame and adapted to normally simultaneously engage the conducting-wire, and a control-cord secured at the outer part of the pole, the arrangement being such that the wheel-frame is pivoted at about its center of gravity and that a straight line connecting the axes of the trolley-wheels intersects the pivot of the wheel-frame.

In testimony of which invention I have hereunto set my hand, at Philadelphia, on this 25th day of August, 1905.

JACOB R. DEILY.
